UNITED STATES PATENT OFFICE.

WILLIAM H. HALL, OF CICERO, ILLINOIS, ASSIGNOR TO THE AMERICAN HOTEL REGISTER CO., OF CHICAGO, ILLINOIS.

LOOSE-LEAF HOTEL-REGISTER DEVICE.

Specification of Letters Patent.

Patented May 6, 1919.

1,302,654.

Application filed June 8, 1918. Serial No. 238,968.

To all whom it may concern:

Be it known that I, WILLIAM H. HALL, a citizen of the United States, residing at Cicero, in the county of Cook and the State 5 of Illinois, have invented certain new and useful Improvements in Loose-Leaf Hotel-Register Devices, of which the following is a specification.

The object of this invention is to provide 10 a light-weight, conveniently handled pad for securely holding loose leaf hotel register sheets on the counter while the arriving guests are registering their names thereon. In hotels having a large number of arrivals 15 per day, they frequently come in crowds. During the process of registering it is necessary for the clerk behind the counter to turn the sheet about many times to mark and to refer to room numbers and other data, 20 and when a sheet has been filled, with other arrivals waiting to register, to quickly remove the filled sheet and replace it with another.

The fundamental features of this invention, 25 and the essential features of a hotel registering device where loose leaves are used, are a pad or holding device to contain the registering sheet, having a smooth surface on which to lay the sheet, and as 30 light in weight and as thin as is consistent with rigidity and durability, with a smooth under surface that will not scratch the counter. Equally important is a means for securely holding the sheet on the pad, so 35 constructed that the sheets may be quickly attached and detached.

To facilitate this quick and convenient handling, the means for holding the sheet should not extend beyond the lines of the 40 pad, nor above its surface more than the necessary thickness of the holding clip and the thickness of the register sheets it holds. The novel features of this invention fully meet these requirements, as will be seen from 45 the following description.

Figure 1 is a top plan view with parts broken away.

Fig. 2 is an end view.

Fig. 3 is a sectional view on the line 3—3,

50 Fig. 1.

In Fig. 1, A is a pad of suitable thickness and somewhat larger than the register sheet,

preferably made of tar board lined with leather.

At one end of this pad an elongated notch 55 is cut. The length and depth of this notch is indicated by the dotted and solid line B, Fig. 1. (The inside wall of this notch is bb, Fig. 3.)

The spring clip holding device, and the 60 manner of attaching it to the pad is shown in detail in Fig. 3. In this figure C is a metal base with its outer edge turned up to give rigidity. D is one of a series of up-turned lugs having holes adapted to receive 65 the hinge rod E. This base piece C extends a considerable distance on the under side of the pad and is attached thereto by means of rivets F. See Fig. 3.

The spring-pressed clip G has downward 70 extending lugs with holes therein adapted to register with the holes in the lugs D of the base part, and is hinged to the base part by means of the rod E, which passes through the holes in both sets of lugs. The springs 75 H hold the front edge of this member G firmly on the registering sheet I, and when it is desired to remove the filled sheet and replace with another, it is easily and quickly done by pressing on the back edge of the 80 holding clip with one hand and changing the sheets with the other.

A holding clip for the purpose herein described cannot be mounted on the top of the pad in the usual way because it would be inconvenient and in the way and entirely unacceptable to the trade. Hence the novel arrangement of combining the two parts—the pad and holding clip—by cutting the elongated notch the length and depth of 90 which is defined by line B, Fig. 1, in one side of the pad into which the hinge, consisting of the rod E, the springs H and the lugs on the two members, fit, thus allowing the base member of the holding clip to rest 95 on the bottom of the pad and be securely attached thereto, while the spring-pressed member extends slightly above the surface with its front holding edge resting firmly on the surface.

I claim—

In a loose leaf hotel register device, a substantial board having an elongated notch cut in one side, a spring-pressed holding

clip adapted to fit into said notch, said clip having a rigid bottom member adapted to extend beyond the inner edge of said notch and be secured to the bottom side of the board, a rocking spring-pressed member hinged to said rigid base, its inner edge extending beyond the inner edge of the slot

in said board and normally resting upon the top surface thereof.

WILLIAM H. HALL.
